UNITED STATES PATENT OFFICE.

JOHN W. BARR, OF PARK CITY, MONTANA.

ROTATABLE WORK-STAND.

1,145,663.

Specification of Letters Patent.

Patented July 6, 1915.

Application filed March 17, 1914. Serial No. 325,367.

To all whom it may concern:

Be it known that I, JOHN W. BARR, a citizen of the United States, and residing at Park City, in the county of Stillwater and State of Montana, have invented certain new and useful Improvements in Rotatable Work-Stands, of which the following is a specification.

This invention relates to new and useful improvements in work stands and more particularly to the class so constructed as to be rotatable and especially adapted to be used in repair shops where engines of different types are frequently handled.

An object of this invention is the provision of a work stand, constructed chiefly of channeled iron thus producing a stand that will prove far superior in strength to that of stands constructed of other material and at the same time producing a stand that will be by far lighter in weight than one constructed of solid iron bars throughout.

A further object of this invention is the provision of a work stand so constructed that it may be conveniently moved to any location desired and then substantially secured thereto.

A further object of this invention is the provision of a work stand, having a rotatable frame so constructed to accommodate and hold thereon engines of different lengths and widths, and furthermore, to permit the mechanic to tilt the stand with engine on same at any angle so as to conveniently allow him to work on any part of the machine. He may completely turn the machine upside down while secured to the frame and work on the underside of the engine if he so desires.

A still further object of this invention is the provision of a work stand so constructed that when the mechanic has completed his work of repairing the engine and is satisfied that the same is now in first-class working order again, he may be still further assured that the same has been properly repaired by applying the wires from the coil to the cylinders of the engine and cranking the same by means of the crank I have applied at one end of my stand, but which crank can be readily removed if desired.

It is now thought that the above objects fully bring out the fact that my workstand will eliminate the unnecessary labor now given mechanics, owing to the fact that at the present time the mechanic has to re-

place the engine in the car before testing it after finishing repairing the same, and furthermore when repairing the top members of the engine, should he have repairing to do on the underside also, he must undoubtedly turn the engine over, which is a laborious task, and which task is entirely eliminated by using a stand as hereinafter more fully described.

With the above and other objects in view, this invention resides in the novel features of construction, formation, combinations, and arrangements of parts to be hereinafter more fully described, claimed and illustrated in the accompanying drawings, in which:

Figure 1, is a side elevation of my rotatable work stand, Fig. 2, is a top plan view of the same, Fig. 3, is a front elevation of the same, Fig. 4, is a perspective view of the foot pedals and coöperating members secured thereto when the pedal 37 at the left is depressed, and Fig. 5, is a perspective view of the crank handle and plate detached.

Referring to the accompanying drawings by similar characters of reference for corresponding parts in all the views, the numeral 10 denotes in general my rotatable work stand, which comprises standards 11 and 12, having pivotally mounted therebetween the frame 13, to which an engine to be worked upon is securely mounted.

The standards 11 and 12 are connected by suitable means at their lower extremities to a longitudinal bar 14, which holds the said standards substantially in spaced relation to each other, while secured substantially beneath this bar 14 at opposite ends thereof and below the standards 11 and 12 are cross bars 15 and 16 substantially braced by braces 17 and having secured to the opposite ends thereof, rollers 19 upon which my stand in general may be conveniently moved as desired, but when in the desired location, the same may be further braced and held substantially in the desired location by an angle iron 20, secured to the intermediate portion of the cross bars 15 and 16 and then to the flooring. The longitudinal bar 14 has also secured to the intermediate portion thereof braces 21 and 22, the outer ends of which are secured to the standards 11 and 12 by any suitable means, thus still further strengthening the said standards, while secured to the said braces 21 and 22 by means

of angular bolts and winged nuts 23 is a waste pan 24 adapted to catch the waste matter discharged from the frame 13, when in use.

5 Secured to the upper ends of the standards 11 and 12 by means of angular plates 25 are outwardly extended trays 26, further supported and strengthened by braces 27 secured to the said standards, these trays being provided for the reception of tools or the like, thus producing a work bench at each end of the stand.

10 Mounted between the standards 11 and 12 and at the upper ends thereof is the frame 13 pivotally secured therebetween by means of bearings 28, secured to the intermediate portion of the horizontally disposed bars 29, which form part of the said frame, together with the longitudinally disposed bars 30. These bearings 28 are for the reception of the bolts 31, operating therein and secured to the standards 11 and 12 by suitable means, thus it will be readily understood that the said frame 13 is rotatable 15 between the standards 11 and 12. This frame 13 consisting of the above mentioned bars 29 and 30 has numerous slots formed therein. The longitudinally disposed slots 32 formed in the bars 30 are for the reception of bolts or the like inserted therethrough from the base of the engine to be worked upon, thereby producing a means for substantially securing the said engine to the said frame, while the length of the 20 slots are produced so that the said frame will accommodate an engine of any size and permit the same to be adjusted thereto. The bars 29 have also formed therein at their opposite ends longitudinally disposed 25 slots 33, but these slots are produced for the purpose of permitting the said bars 30 to be adjusted thereon so that the said frame 13 may be adjusted to the width of any engine mounted thereon, and all of the said bars 30 have also formed therein a series of smaller 30 slots 34 for the reception of bolts substantially holding in position thereon braces 35, which are adjusted thereto by means of the winged nuts 36. These winged nuts I apply 35 for convenience so that the said braces may be readily adjusted.

It will be noted that the standard 12 is provided with a pair of foot pedals 37, made of resilient material as clearly illustrated in 40 Fig. 4 of the accompanying drawings. It will also be noted that the pedals are made substantially from one piece of material, thus producing spring levers, which are secured to the standard 12 by a bolt or the like 37, passing through the aperture 38, formed by looping the said levers, said bolt forming a pivot on which the levers turn. Said levers are still further looped so as to produce a spring 39, the undesired movement of which is checked by a guide link

40, having a longitudinally disposed slot 41, formed therein to permit the downward movement of the releasing lever designated by the letter A, while the spring 39 forces the operating link 44 upwardly, the same 70 being guided by a slot 27' formed in the brace 27, secured to the standard 12 and supporting the tray 26, and forcing the dog 45 pivotally mounted in the small standard into connection with the toothed wheel 49, 75 which will be later described. The standard 12 also has a slot 47 formed therein to permit the tongue 48 of the dog 45 to freely operate therethrough in order that the same may engage the teeth of the toothed wheel 80 49 previously mentioned and which is rotatably mounted upon the bolt 31, secured to the standard 12 and operating in the bearing 28 and it is to be understood that the said wheel 49 rotates with the frame 13, owing to 85 the fact that it is substantially secured to the bearing 28, which as before stated is secured to a member, comprising a part of the said frame. The standard 12 is also of greater length than the opposite standard 90 11, this extra length having apertures formed therein for the reception of bolts 49' to secure thereto an extra plate 50, also having similar apertures formed therein and also the customary auto crank handle 51 95 mounted therein at its upper end, the object of which will be hereinafter more fully described as well as that of the customary coil 52 substantially mounted on the opposite standard 11.

100 The operation of my work stand is as follows:—The stand is first moved to the desired location in the shop and may be substantially secured thereto, if so desired, by means of the angle irons. When in position, the engine to be worked upon, is removed from the car and placed upon the frame 13, which is at once adjusted to fit the base of the said engine, then the bolts are passed through the base plate of the engine and through the slots in the bars 30 of the frame 13 and fastened thereto by a suitable means, then the engine is in readiness to be worked upon.

110 The frame is always kept from rotating, 115 when its rotation is not desired, by the tongue 48 in contact with the toothed wheel, this being due to the fact that the spring co-operating with the said tongue forces the tongue into engagement with the teeth of 120 the said wheel, but when it is desired to turn the engine at an angle, or to turn the same completely over so as to get at the underside, the operator presses the foot pedal, which operates the releasing lever A, 125 which in turn releases the tongue by means of the operating link 44, thus permitting the entire frame 13, and engine mounted thereon, and secured thereto, to rotate between the standards 11 and 12 until in the desired 130

position, then upon removing pressure from the foot pedal, operating the releasing lever, the spring at once forces the tongue 48 back into engagement with the teeth; and to further force the said tongue 48 into engagement, the operator presses the opposite foot pedal, which forces the tongue into positive engagement as well as strengthens the spring considerably, while applying this pressure.

- 10 After the engine has been repaired, in order to ascertain that the same has been properly repaired, I apply the plate carrying the crank handle to the standard 12 and forcing the same into engagement with the proper member and having the wires from the coil properly connected with the said engine, I feed into the cylinders a suitable amount of fuel and crank the engine. Thus it will be readily seen that the engine is now 20 in operation while on the work stand, and should it need further repairing after this test, the same may be done at once by merely stopping the engine, thus eliminating the extra labor produced by having to 25 set the engine into the car and then try it out.

It is now thought that the above description of the operation of my work stand together with the accompanying drawings is 30 sufficient to give those familiar with this art a clear idea as to the operation of my device. It should be understood, however, in this connection that various minor changes in the details of construction may be 35 resorted to within the scope of the appended claims, without departing from or sacrificing any of the advantages of this invention.

From the foregoing disclosure taken in 40 connection with the accompanying drawings, it will be manifest that I have provided a rotatable work stand, adapted to be used in connection with the repairing of automobile engines or the like and which will fulfil all of the necessary requirements of 45 such a device.

Having thus fully described this invention, what I claim as new and wish to protect by Letters Patent, is:—

1. A work stand comprising a plurality of cross bars supporting a longitudinally disposed bar, a plurality of standards mounted thereon, a plate secured to one of the said standards and having a crank handle operating therein for connection with an engine, a frame rotatably mounted between the said standards and adapted to hold the said engine in such a position so as to be operated by the said crank handle, and an operating means for the same.

2. A work stand comprising a plurality of cross bars supporting a longitudinally disposed bar, a plurality of standards mounted thereon, a frame rotatably mounted between the said standards, a toothed wheel secured thereto, a plurality of spring levers secured to one of the said standards and having foot pedals formed thereon, a link connected to the said spring levers, and a dog secured to and operated by said link for engagement with the said toothed wheel.

3. A work stand comprising a plurality of cross bars supporting a longitudinally disposed bar, a plurality of standards mounted thereon, a rotatable frame mounted between the said standards and composed of a series of longitudinally and horizontally disposed bars, a plurality of bearings secured to the said horizontally disposed bars, a toothed wheel secured to one of the said bearings, a dog adapted to engage the teeth of the wheel to hold the said rotatable frame rigid, and foot operated means for operating the dog.

In testimony whereof I affix my signature in presence of two witnesses.

JOHN W. BARR.
